VARIABLE ACOUSTICAL REVERBERATION SYSTEM

Arthur Pfister, Woodside, N. Y., assignor to Radio Corporation of America, a corporation of Delaware

Application March 21, 1935, Serial No. 12,211

17 Claims. (Cl. 179—1)

This invention relates to the science of acoustics and deals more specifically with the reverberation of sounds in enclosed spaces and means for control of same in conjunction with or by means of electrical circuits.

In present-day broadcasting, which usually takes place in studios which have been acoustically treated to reduce reverberation, it is frequently desirable to change the acoustical characteristics of the studio rapidly during the course of the program in order that these characteristics may correspond to the type of program presented and thus convey to listeners the realism necessary for complete enjoyment of the program.

In the past, such changes have been attempted by two different methods, neither of which has proved entirely satisfactory because of the practical and technical limitations.

The first method, which is simple and widely used, employs a variable sound absorbing medium in the studios, such as drapes, sliding panels of other similar sound absorbing materials. This permits variation of the reverberation time but only over a limited range.

In the second method, which is infrequently used, a portion of the sound equivalent electrical energy of the program is radiated by a loud speaker in a highly reverberant room or studio for the express purpose of obtaining reverberation. There the program is again picked up by a microphone and reconverted into electrical energy which is then mixed, in the desired proportion, with a portion of the original output of the studio. This method permits control of the reverberation amplitude but not the reverberation time since that depends upon the dimensions of the reverberation chamber and its surface material.

My present invention, which is a substantial improvement over the two methods mentioned above, is accomplished by comparatively simple means and it permits the control of the reverberation time lag, as well as the amplitude and duration. In addition, it has other superior advantages which will be more fully outlined herein-after.

The invention will be more thoroughly understood by referring to the accompanying drawing, in which Fig. 1 illustrates diagrammatically one form of my present invention. Fig. 2 is a partial modification of Fig. 1, in which separate acoustic delay circuits have been combined into a single delay circuit.

Referring now in detail to the schematic diagram, Fig. 1, 1 represents the purposely highly damped room or studio whose acoustical char-

acteristics are to be varied. Sound is picked up by microphone 2, converted into electrical energy and passed through amplifier 3, volume control 4 and amplifier 5. A portion of the output energy of amplifier 5 is diverted at a point 6, passed through an amplifier 7 and then through volume controls 8A, 8B, 8C, to electro-acoustical transducers 9A, 9B, 9C, respectively. These feed the respective acoustic delay circuits 10A, 10B, 10C, which are of unequal length and which terminate respectively in the exponential acoustical couplings 11A, 11B, 11C. The orifices of 11A, 11B, 11C, are part of the wall surfaces of reverberation chamber 12 where the radiated sound is picked up by microphone 13 and reconverted into electrical energy which passes through amplifier 14 and volume control 15 and is then combined at point 16 with a portion of the original energy which has passed through the isolating amplifier 19. The combined signal then passes through amplifier 17 to the program bus 18.

Having thus described the elementary set-up of the apparatus involved, the manner in which the invention functions will be explained. Referring again to the diagram of Fig. 1, all equipment within the dashed lines is of standard type and essential to broadcasting. All equipment outside of these lines is accessory, although much of it is also of standard type, and serves to carry out the intention of the invention. The 25 electro-acoustical transducers 9A, 9B, 9C, controlled respectively by volume controls 8A, 8B, 8C, receive their energy from tap 6 and radiate sound energy into acoustic delay circuits 10A, 10B, 10C. These, in their preferred forms, are 30 tubes of non-resonating material of unequal length, the inner surfaces of which have a smooth and hard finish to insure satisfactory and uniform sound transmission.

The acoustical couplings 11A, 11B, 11C, connecting the acoustical delay circuits 10A, 10B, 10C, with reverberation chamber 12 are of exponential form with their orifices preferably mounted flush with the wall, or walls, of the reverberation chamber in compliance with the 45 laws of acoustics for coupling transmission lines of unequal dimensions. By virtue of this arrangement, sound can travel in practically one direction only, namely, from 9A, 9B, 9C through 10A, 10B, 10C, and 11A, 11B, 11C, into reverberation chamber 12. As the name implies, this chamber is highly reverberant due to reflecting wall surfaces and, consequently, sound entering through 11A, 11B, 11C, decays at a slow rate. Microphone 13 reconverts into electrical energy 55

the sound which is radiated into 12 by 11A, 11B, 11C, and this is then passed through amplifier 14 and volume control 15 to junction 16 which it is combined with a portion of the original sound equivalent energy which has passed through the isolating amplifier 19. The combined signal then passes through amplifier 17 to the program bus 18. The output level of the isolating amplifier 19 is usually adjusted to be equal to the input level in order that the unit may perform the function of isolation without altering the energy level normally existing at the input of amplifier 17.

In summarizing the action it is now evident that by diverting at point 6 a portion of the sound equivalent electrical energy from 2 and reconverting the same through electro-acoustic transducers 9A, 9B, 9C, it is possible to obtain in acoustical circuits 10A, 10B, 10C, a delay with respect to source 2 which will depend upon the lengths of circuits 9A, 9B, 9C, and the type of transmission medium used which, in its simplest form, may be air. It is also evident that, without occupying excessive space, the delay circuits 25 may be made any desired length, within practical limits, and thus simulate in any desired proportion the dimensions of a room. Similarly, combinations of various acoustical delay circuits may be arranged to simulate rooms of almost any 30 variety.

Furthermore, by adding reverberation in chamber 12 to signals suitably delayed in circuits 10A, 10B, 10C, signals may be picked up by microphone 13 which faithfully resemble those 35 which would be picked up by microphone 2 in room 1 but possessing such additional characteristics as are produced by the interposition of one or a combination of acoustical delay circuits, as for instance 9A/11A, 9B/11B, 9C/11C, and such 40 reverberation characteristics as are obtained in chamber 12. These reverberation characteristics can be varied by means of drapes, sliding panels, etc.

As a result, there is available at junction 16 45 and in program circuit 18 a signal adjustable electrically in reverberation amplitude, duration and time lag.

A modification of the above circuit arrangement is shown in Fig. 2, wherein the separate 50 acoustic delay circuits have been combined into a single delay circuit 110 and the individual electro-acoustic transducers 109A, 109B, 109C, radiate sound into said delay circuit at points 55 unequally distant.

Although this invention has been described setting forth certain modifications, it is to be distinctly understood that the invention is not to be limited except as to those limitations which are clearly set forth in the appended claims.

What I claim is:

1. In a system for translating sound into characteristic electrical energy and for alternating the characteristics of the system electro-acoustically, an electrical circuit, means for deriving from a certain point in the electrical circuit a portion of said characteristic electrical energy, means for feeding said derived energy through an amplifier circuit to a plurality of electro-acoustical transducers, a plurality of 65 tubes forming a plurality of acoustical delay circuits coupled to said transducers, each one of said tubes being of unequal lengths to give a variety of delay times unequally long with respect to each other and to any given point of the 70 delay circuit.

2. In a system for translating sound into an equivalent electrical energy and for alternating the characteristics of the system electro-acoustically, said system having means deriving from a certain point in the electrical circuit a portion 5 of sound equivalent electrical energy, means for feeding said energy through an amplifier circuit to a plurality of electro-acoustical transducers, a plurality of tubes forming a plurality of acoustical delay circuits connected to said transducers, each one of the tubes being of unequal lengths to give a variety of delay times unequally long with respect to each other and to any given point of the delay circuit and means for unifying in a single self-contained enclosure of suitable design the two distinctly separate functions of time delay and reverberation.

3. In a system for translating sound into an equivalent electrical energy and for alternating the characteristics of the system electro-acoustically, said system having means deriving from a certain point in the electrical circuit a portion of sound equivalent electrical energy, means for feeding said energy through an amplifier circuit to a plurality of electro-acoustical transducers, a 20 plurality of tubes of resonating material forming a plurality of acoustical delay circuits connected to said transducers, each one of the tubes being of unequal lengths to give a variety of delay times unequally long with respect to each other and to any given point of the delay circuit and means for isolating acoustically the distinctive separate functions of time delay and reverberation by means of an exponential acoustical 25 coupling between the respective sections of the 30 circuit.

4. In a system for translating sound into an equivalent electrical energy and for alternating the characteristics of the system electro-acoustically, said system having means deriving from a certain point in the electrical circuit a portion of sound equivalent electrical energy, means for feeding said energy through an amplifier circuit to a plurality of electro-acoustical transducers and a plurality of tubes forming a plurality of acoustical delay circuits, each tube being of unequal lengths to give a variety of delay times 45 unequally long with respect to each other and to any given point of the delay circuit, means for unifying in a single self-contained enclosure of suitable design the two distinctly separate functions of time delay and reverberation, an exponential acoustical coupling between the respective sections of the acoustical circuit which is provided for the functions of delays and reverberations for the purpose of rendering the system unidirectional to sound waves in a chosen 50 direction.

5. In a system for translating sound into an equivalent electrical energy and for alternating the characteristics of the system electro-acoustically, said system having means deriving from a certain point in the electrical circuit a portion of sound equivalent electrical energy, means for feeding said energy through an amplifier circuit to a plurality of electro-acoustical transducers and a plurality of tubes forming a plurality of acoustical delay circuits, each tube being of unequal lengths to give a variety of delay times 65 unequally long with respect to each other and to any given point of the delay circuit, means for unifying in a single self-contained enclosure of suitable design the two distinctly separate functions of time delay and reverberation, an exponential acoustical coupling between sections of 70

75

- an acoustical circuit of unequal dimensions to obtain faithful sound transfer from one section to another.
6. In a system for translating sound into an equivalent electrical energy and for alternating the characteristics of the system electro-acoustically, said system having means deriving from a certain point in the electrical circuit a portion of sound equivalent electrical energy, means for feeding said energy through an amplifier circuit to a plurality of electro-acoustical transducers and a plurality of tubes having a hard inner surface forming a plurality of acoustical delay circuits, each being of unequal lengths to give a variety of delay times unequally long with respect to each other and to any given point of the delay circuit and an isolating amplifier between that point in the circuit where a portion of the sound equivalent electrical energy is diverted for the purpose of obtaining an acoustic delay and that point in the circuit where the delayed energy is combined with a portion of the original energy.
7. In a system for translating sound into an equivalent electrical energy and for alternating the characteristics of the system electro-acoustically, said system having means deriving from a certain point in the electrical circuit a portion of sound equivalent electrical energy, means for feeding said energy through an amplifier circuit to a plurality of electro-acoustical transducers, a plurality of horns forming acoustical delay circuits connected to said transducers, each horn being of unequal lengths to give a variety of delay times unequally long with respect to each other and to any given point of the delay circuit and means for varying the reverberation time of the reverberation chamber by means of a system of drapes within said reverberation chamber.
- 40 8. In a system for translating sound into an equivalent electrical energy and for alternating the characteristics of the system electro-acoustically, said system having means deriving from a certain point in the electrical circuit a portion of sound equivalent electrical energy, means for feeding said energy through an amplifier circuit to a plurality of electro-acoustical transducers, a plurality of horns forming acoustical delay circuits connected to said transducers, each horn being of unequal lengths to give a variety of delay times unequally long with respect to each other and to any given point of the delay circuit and means for varying the reverberation time of the reverberation chamber by means of a system of sliding panels within said reverberation chamber.
9. In a system for translating sound into an equivalent electrical energy and for alternating the characteristics of the system electro-acoustically, said system having means deriving from a certain point in the electrical circuit a portion of sound equivalent electrical energy, means for feeding said energy through an amplifier circuit to a plurality of electro-acoustical transducers feeding into a plurality of tubes forming acoustical delay circuits, each tube being of unequal lengths to give a variety of delay times unequally long with respect to each other and to any given point of the delay circuit and means for varying the reverberation time of the reverberation chamber by the use of sound absorbent material within said reverberation chamber.
- 10 10. In a system for translating sound into equivalent electrical energy, means for altering the characteristics of the system electro-acousti-

cally, said system comprising means for deriving from a certain point in the electrical circuit a portion of sound equivalent electrical energy, means for feeding said portion of energy through an amplifier circuit to an electro-acoustical transducer and into a plurality of tubes of unequal lengths forming an acoustical delay circuit, said acoustical delay circuit being acoustically coupled to an enclosed chamber capable of producing reverberation of sound energy and means for reconverting the reverberant sound into electrical energy and applying a certain portion thereof to the first-mentioned electrical circuit at a certain point other than the first-mentioned.

11. In a system for translating sound into proportionately equivalent electrical energy, said system having means for altering the acoustical properties of the system electro-acoustically by deriving from a certain point in the electrical circuit a portion of sound equivalent electrical energy, means for feeding said portion of energy through an amplifier to a plurality of electrical control means and into a plurality of electro-acoustical transducers, a plurality of tubes of unequal lengths forming acoustical delay circuits connected to said electro-acoustical transducers, said acoustical delay circuits being acoustically coupled to an enclosed chamber capable of producing reverberation of said sound energy, means for reconverting the reverberant sound into electrical energy and applying a certain portion thereof to the first-mentioned electrical circuit at a certain point other than the first-mentioned.

12. A sound translating system having in combination a microphone, volume control means, an amplifier circuit and a program output circuit, a plurality of acoustical delay circuits connected to said amplifier, said acoustical delay circuits comprising a tube having a plurality of electro-acoustical transducers located at different points along said tube, an enclosed chamber acoustically coupled to said tube, a second microphone within said chamber, a second amplifier circuit connecting said second microphone to the output program circuit substantially near the point where said acoustical delay circuits join said first mentioned amplifier.

13. A sound translating system having in combination a microphone located in a studio, volume control means, an amplifier circuit and a program output circuit, a plurality of acoustical delay circuits connected to said amplifier, said acoustical delay circuits comprising a plurality of tubes each one being of a different length, having a plurality of electro-acoustical transducers located at one end of said tubes, an enclosed chamber acoustically coupled to the other end of said tubes, a second microphone within said chamber, a second amplifier circuit connecting said second microphone to the output program circuit substantially near the point where said acoustical delay circuits join said first mentioned amplifier.

14. A sound translating system having in combination a microphone located in a studio, an amplifier circuit and a program output circuit, a plurality of acoustical delay circuits connected to said amplifier, and a plurality of volume control devices connecting said amplifier to said acoustical delay circuits comprising a plurality of tubes each one being of a different length, having a plurality of electro-acoustical transducers located

at one end of said tubes, an enclosed chamber acoustically coupled to the other end of said tubes, a second microphone within said chamber, a second amplifier circuit connecting said second microphone to the output program circuit substantially near the point where said acoustical delay circuits join said first mentioned amplifier.

15. A sound translating system having in combination a microphone located in a highly damped room, an amplifier connected to said microphone, an amplifier circuit having a junction point and a program output circuit, a plurality of electro-acoustical transducers connected to the junction point of said amplifier circuit, a plurality of tubes 10 one end of which acoustically joins said transducers, the other end of said tubes being acoustically connected to a reverberation chamber, a circuit connecting said second microphone with the junction point of said amplifier circuit to be 15 combined with a portion of the sound energy electrical impulses of said first mentioned microphone, the impulses of both microphones being mixed and passed to said program output circuit.

16. A sound translating system having in combination a microphone located in a highly damped room, an amplifier and a volume control device connected to said microphone, an amplifier circuit having a junction point and a program output circuit, a plurality of electro-acoustical transducers connected to the junction point of said 20 amplifier circuit, a plurality of tubes one end of 25

which acoustically joins said transducers, the other end of said tubes being acoustically connected to a reverberation chamber, a second microphone located within said reverberation chamber, a circuit connecting said second microphone with the junction point of said amplifier circuit to be combined with a portion of the sound energy electrical impulses of said first mentioned microphone, the impulses of both microphones being mixed and passed to said program output 10 circuit.

17. A sound translating system having in combination a microphone located in a highly damped room, an amplifier connected to said microphone, an amplifier circuit having a junction point and 15 a program output circuit, a plurality of electro-acoustical transducers connected to the junction point of said amplifier circuit, a plurality of tubes of non-resonating material one end of which acoustically joins said transducers, the other end 20 of said tubes being acoustically connected to a reverberation chamber, a second microphone located within said reverberation chamber, a circuit connecting said second microphone with the junction point of said amplifier circuit to be combined with a portion of the sound energy electrical impulses of said first mentioned microphone, the impulses of both microphones being mixed and passed to said program output circuit.
